UNITED STATES PATENT OFFICE.

SAMUEL N. SHEELY, OF PORTSMOUTH, VIRGINIA.

KEEL-BLOCK.

1,253,540.

Specification of Letters Patent. Patented Jan. 15, 1918.

Application filed June 26, 1917. Serial No. 177,105.

To all whom it may concern:

Be it known that I, SAMUEL N. SHEELY, a citizen of the United States, residing at Portsmouth, in the county of Norfolk and 5 State of Virginia, have invented new and useful Improvements in Keel-Blocks, of which the following is a specification.

The present invention relates to keel blocks capable of supporting ships during 10 the building construction thereof, and designed primarily to produce means for preventing any accidental lateral movement of the blocks with respect to the core section, during the action of removing the blocks 15 from beneath the ship when the same is complete for launching.

The primary object of the invention, among other features, contemplates the production of a block embodying a novel form 20 of core, which affords the operation of the blocks at the proper time without necessitating the service of a considerable number of laborers.

A further object of the invention resides 25 in the provision of a keel block, which, aside from overcoming the necessity of the employment of a large force of laborers, is simple in construction, durable and efficient in use and may be quickly and expeditiously 30 removed from beneath the keel at the proper time.

With the above and other objects in view, the invention consists in the novel features, 35 details of construction and combination of parts which will hereinafter be more fully set forth, illustrated in the accompanying drawing and pointed out in the appended claims.

Figure 1 is a perspective view of the keel 40 block with the keel shown in dotted lines;

Fig. 2 is an end view;

Fig. 3 is a perspective view of the core; and

Fig. 4 is a section taken on line 4—4 of 45 Fig. 1.

Referring more particularly to the drawing, wherein is illustrated the preferred embodiment of the invention, the keel block generally is denoted by the character 5 embodying a support or cross section 6 of substantially diamond-shape presenting the same on the upper and lower portions thereof with longitudinally extending inclined faces 7 and 8 respectively, the faces on both 55 the upper and lower portions of the core tapering from the transverse center thereof

in a downward direction toward the transverse ends 9 of the core. Extending through the longitudinal center of the core is an adjusting screw 10 mounted in the substantially circular bore 11 of the core, and journaled in the bore of a nut 12 seated within a substantially squared or rectangular recess traversing the core and intersecting with the longitudinal bore 11 thereof. Ex- 60 tending along the longitudinal center and formed integral with each of the respective faces 7 and 8 thereof, is a longitudinally extending dove-tailed tongue 13 adapted to engage in a dove-tailed recess 14 provided 65 in each of the plurality of movable members 15. The movable members in this particular instance are of substantially wedge-shaped form and having their confronting faces gradually tapering from the outer 70 ends 16 thereof in a direction toward the meeting ends 17, consequently, when the wedges are in assembled position, a pair of these members will be slidably reposed upon the respective inclined faces 7 and 8 of the 75 core member. Provided in the outer end of each wedge or movable block member 15, is a substantially U-shaped recess 18, which, when the blocks are in assembled form, will provide at the ends of the core member a 80 substantially rectangular guide-way 19 in which is loosely mounted a connecting plate 20 provided centrally with a threaded aperture 21. Due to the fact that the adjusting screw 10 exceeds the length of the core mem- 85 ber 6, permits of the reversely threaded ends 22 thereof to threadedly engage in the aperture 21 of the connecting plate 20, hence, 90 when the building construction of the ship is completed and the launching of the vessel 95 is desired, by manipulating the adjusting screw 10, will cause the blocks or members 15 to simultaneously move in a longitudinal direction with respect to the core member and displace the blocks from contact with 100 the keel of the ship. Furthermore, by the provision of the tongue and groove connection denoted respectively by the characters 13 and 14, prevents the wedges or block members 15 from moving laterally with respect to the core during the manipulation 105 of the adjusting screw 10.

From the foregoing description, taken in connection with the accompanying drawing, the advantages of construction and the 110 method of operation will be readily apparent to those skilled in the art to which

the invention relates, and while I have described the principles of operation of the invention, together with the device which I now consider to be the best embodiment thereof, I desire to have it understood that the device shown is merely illustrative, and that such changes may be made when desired as are within the scope of the appended claims.

10 1. What is claimed as new is:—

15 1. In a device of the class described, comprising a core provided with a longitudinal and a transverse bore intersecting one another at the transverse center of the core, a plurality of movable wedges mounted on said core, a bearing in the transverse bore of the core, and an adjusting screw journaled in said bearing and located in the longitudinal bore of the core for effecting 20 the adjustment of the members in a longitudinal direction of the core.

25 2. In a device of the class described, comprising a diamond-shaped core, provided with a longitudinal and a transverse bore intersecting one another at the transverse center of the core, a plurality of movable wedges mounted on said core, a bearing in the transverse bore of the core, and an adjusting screw journaled in said bearing and located in the longitudinal bore of the core for effecting 30 the adjustment of the members longitudinally of and in a direction toward the free transverse edges of the core.

35 3. In a device of the class described, comprising a diamond-shaped core provided with a longitudinal and a transverse bore intersecting one another at the transverse center of the core, a plurality of movable wedges mounted on said core, a bearing in the transverse bore of the core, an adjusting screw journaled in said bearing and located in the longitudinal bore of the core

for effecting the adjustment of the members longitudinally of and in a direction toward the free transverse edges of the core, and 45 means for preventing any movement of the wedge-shaped members in a direction laterally of the core.

4. In a device of the class described, comprising a diamond-shaped core provided 50 with a bore, an adjusting screw of a length exceeding the length of the bore being mounted within the bore thereof positioning the extremities thereof beyond the free transverse edges of said core, the extended 55 extremities of the adjusting screw being oppositely threaded, a plurality of wedge-shaped members movably mounted on said core, and means loosely mounted in the ends of the wedges and in which the reverse 60 threaded ends of the adjusting screw engage for imparting a spreading or contracting action to the wedge-shaped members.

5. In a device of the class described, comprising a diamond-shaped core provided 65 with a bore, an adjusting screw of a length exceeding the length of the bore being mounted within the bore thereof positioning the extremities thereof beyond the free transverse edges of said core, the extended 70 extremities of the adjusting screw being oppositely threaded, a plurality of wedge-shaped members movably mounted on said core, and means loosely mounted in the ends of the wedges and in which the reverse 75 threaded ends of the adjusting screw engage for imparting a spreading or contracting action to the wedge-shaped members, said last named means further producing a simultaneous operation of said wedge-shaped members upon the manipulation of the adjusting screw.

In testimony whereof I affix my signature.
SAMUEL N. SHEELY.
